REMOTE CONTROL SYSTEM

John B. N. Cardoza, New York, N. Y.

Application August 13, 1929, Serial No. 385,619

8 Claims. (Cl. 104—151)

This invention relates to a system of remote control and particularly to a system wherein the operation of a plurality of devices are controlled from a central point over a single circuit.

5 The object of the invention is to provide a system of control that is relatively simple and cheap to manufacture and install and which utilizes for its component parts standard types of apparatus easily assembled to produce the desired 10 result.

Another object is to provide a system wherein electrically actuated mechanism is employed to effect the remote control of parts of the apparatus over a simple circuit thereby eliminating individual manual control thereof and a plurality of circuits, or both.

A further object is to provide a system in which the circuit wiring is reduced to a minimum and which is therefor adapted for use with existing 20 systems such as railroads and the like.

Further objects and advantages will more fully hereinafter appear.

To illustrate the invention it will be described as applied to a railroad system and particularly 25 to a toy electric railroad system. This is shown merely for the sake of illustration as the invention is applicable to a large variety of uses where it is desired to control a plurality of devices from a control point, over a single circuit.

30 In my pending application, Ser. No. 240,786, filed December 17, 1927, is described a control system applied to toy trains and the possible sequential operations of two such trains on a single track is therein described in detail. In the instant application we shall describe further modifications and improvements in the operation of toy trains as described in the aforesaid application, as well as certain improvements eliminating the necessity for step-by-step selection.

40 In the accompanying drawings which illustrate the invention in a diagrammatic way as applied to the operation of two trains,

Fig. 1 is a diagrammatic view of two trains and the control apparatus therefor.

45 Fig. 2 is a diagrammatic view of a modified form of control mechanism.

The numerals 1 and 2 denote the usual rails or track. 3 is the trolley wire or third rail. (This is usually in toy train systems, positioned between 50 the tracks 1 and 2 insulated therefrom.)

4 and 5 are the usual driving and/or truck wheels of the locomotive and 6 the trolley wheel, third rail contact wheel or shoe.

The tracks 1 and 2 are in electrical contact 55 with each other and form one side of a circuit

to the locomotives, the circuit being completed via the third rail 3. Such a circuit arrangement is now standard practice and one of the advantages of this system is that no changes are necessary in the track equipment when putting the 5 system in use on existing railroads.

The apparatus shown within the dotted line A is that employed upon a single locomotive; that enclosed by line B, another locomotive. The apparatus in both locomotives may be identical in 10 operation and function, but is shown slightly different in the figure to illustrate a modification of the whistling arrangement.

As a source of power for the locomotive motors, the direct current generator 7 is provided 15 connected in the usual manner to rails 1, 2 and third rail 3. Alternating current of proper voltage and frequency can also be used.

A circuit may now be traced from generator 7 (Fig. 1) via tracks 1, 2 to wheels 4, 5 of locomotive B, to conductor 8 to selector brush 9, to brush 10, through the motor field F, to brush 11, to brush 12, through motor armature 13, via conductor 14 to impedance coil 15 and via conductor 16 to contact 6 and via rail 3 to the generator 7. 20

Current from the generator 7 flowing in this circuit will energize the motor F, 13 and cause the locomotive to move forward (the gearing between motor and truck wheels is not shown as it 25 may be of any suitable form and forms no part of this invention).

Now referring to locomotive A, here the selector switch drum 17 is in such a position that the armature and field connections of the motor are reversed as compared to B in relation to the 30 circuit wires 8, 14 and therefore the rotation of the motor is reversed and locomotive A will move backwards, or in a reverse direction to locomotive B.

To effect control of the locomotives, we employ a source of current in addition to generator 7, this additional source of current being of such a character that with the use of an impedance coil, the operation of the locomotive motors is 35 not affected. A suitable source of current may be the alternating current generator 18 and to provide for a plurality of controls for one locomotive or for controlling a plurality of locomotives, I provide additional generators 19, 20, 21. These 40 four generators may be of the type commonly used in telephony for the so-called "harmonic" ringing system, and may generate currents of any suitable voltage, current and frequency. Suitable frequencies in common use are 16 1/2, 50 45

33 1/3, 50, 66 2/3. Obviously, more than four generators may be employed.

These generators are bridged across the track and third rail circuit as shown, a short circuit of the D. C. generator 7 being prevented by suitable condensers or other means usually placed in the generator lead as at 1c.

To effect control of the locomotives (suppose it is desired to reverse the direction of B) key 22 is depressed, and A. C. current at a frequency of 66 2/3 cycles (or any other desired frequency) is momentarily impressed upon tracks 1, 2 and 3 and via conductors 8 and 10 passes into locomotive B. As this current cannot find a path 15 through impedance 15 it flows via conductor 23 through frequency relay 24 and condenser 25, thereby energizing 24, (which is responsive to this frequency only) which closes its normally open contacts 26. D. C. current (the track circuit always being live) now flows from conductor 14 via conductor 27 through solenoid 28 to conductor 8, causing solenoid 28 to energize its plunger 29, actuating the ratchet wheel 30 which moves controller drum 17, changing the connections to 25 brushes 9, 10, 11, 12, to that shown in A and thereby reversing the motor connections in B, and thereby reversing the direction of movement of the locomotive on the track.

The selector switch mechanism is only shown 30 diagrammatically. Any suitable mechanism either rotary, step-by-step, or relay combination may be used to accomplish the desired result. The selector switch drum may have one "dead" position whereby the motor circuits are opened, 35 stopping the motor. (The D. C. supply to the tracks is not broken.)

The arrangement of the controller drum 17 and the cooperating brushes 9, 10, 11, 12, may be such that any desired combination or sequence 40 of contacts can be made, and more particularly the combinations as described in my application Ser. No. 240,786 hereinbefore mentioned.

The selector switch is caused to pass through all its positions in sequence, by repeatedly pressing 45 the key 22 which momentarily energizes the frequency relay 28 as just described.

If each locomotive has a relay responsive to current of the same frequency, then each locomotive is controlled by the relative position of the 50 selective switch.

If each locomotive has a relay responsive to current of a different frequency then the control is effected by a combination of frequency selection and selector switch position.

55 The relay 24 is shown diagrammatically. Any suitable mechanism responsive to the current used for the control (as distinguished from the current used for actuating the motors) may be used and while we have shown only one relay responsive to each frequency in each locomotive, it will be understood that a plurality of relays of different frequencies may be employed in each locomotive, to cause a certain selection of circuits, or each locomotive may have only one relay responsive to one frequency to cause a certain sequence of selection. In the latter case, four locomotives may be operated on one system and each controlled independently of the others, each being controlled by one of the generators 18, 19, 20, 21.

70 At the same time each locomotive can be made to go forward, reverse or stop, by contacting the keys 22, 31, 32, 33 respectively, controlling it and thereby operating its selector switch and controlling its motor.

75 To ring the bell or blow the whistle of a loco-

motive, a certain frequency may be used, relay 34 being responsive thereto, and condenser 35 being arranged in circuit, and operated by one of the frequency generators same as relay 24. The contacts 36 of 34 control a whistle or bell indicated at W in B.

If desired, the relay 34 and condenser 35 may be dispensed with, and a switch magnetic buzzer giving a whistle effect bridged direct on the locomotive circuit in series with condenser 35 as shown in locomotive A. By impressing a current of suitable frequency upon the track circuit the device 37 can be caused to emit a whistle at any time without affecting the operation of the selector switches or frequency relays in this or any of the other locomotives in the system.

In the foregoing system, control is effected by—

- (a) A selector switch having a plurality of positions which can only be attained in sequence.
- (b) A frequency relay controlling the selector switch.
- (c) A manual control for the frequency relay whose impulses, manually controlled, operate the selector switch.

In Fig. 2 I show a modification of the system wherein the selector switch has a plurality of positions but these do not have to be selected in sequence, as it is the case with the step-by-step switch of Fig. 1.

In Fig. 2 the motor 39, 40 is connected to the selector switch contacts 41, 42, 43, 44, as shown. The selector drum 45 is arranged with three positions, "stop", "forward" and "reverse". This drum is connected by shaft 46 to the disc 47 to which are connected the cranks 48, 49, 50, of the solenoid plungers 51, 52, 53. The solenoids 54, 55, 56, preferably positioned 120° apart, are each controlled by a frequency relay, one of which is designated by the numeral 57. This relay when actuated by current of the proper frequency, will close its contacts and cause its associated solenoid 56 to draw in its plungers 52 which through 49, 47, 46, actuates the controller drum 45, and brings the motor circuit to a given position, say "reverse". For purposes of illustration I indicate three sources of current of different frequencies by the conventional symbols for generators bearing reference numerals 67, 68 and 69 which are adapted to be connected to the line by operation of the switches 70, 71 and 72. The generator 67 may produce a current to which only relay 57 is responsive while generators 68 and 69 may be used to control only relays 58 and 59 respectively.

It will now be obvious that with the arrangement shown in Fig. 2 no definite sequence of operations need be gone through. If it is desired to go from "stop" to "reverse" it can be done without making the selector switch assume the "forward" position. Also that regardless of the number of times the button 70 is pushed to actuate relay 57, the selector switch will only assume the "reverse" position. Here the control is effected by:

- (a) A selector switch having a plurality of positions.
- (b) A frequency relay controlling the selector switch.
- (c) A manual control for the frequency relay, whose impulses control only one position of the selector switch.

It will be understood that respective relays controlling the selector switch are each opaque to all but the particular frequency for which each is designed, and while all are connected to the same circuit only the relay designed for the particular frequency impressed upon the track circuit, will operate.

What I claim is:

1. A system of control comprising in combination, a railway track and return circuit, a plurality of devices carried by said track and adapted to be controlled thereon, a three position selector switch on each device, means for selecting the position of each switch, a source of power connected to track and return circuit for operating said devices and said switches, a second source of power for actuating said selecting means bridged across said track circuit and means for manually controlling said last source of power to effect actuation of said switches to any position desired.

2. A system of control comprising two conductors, motors connected thereto, a three position switch for controlling each motor, switch operating means associated with each switch and adapted to be connected to the motor circuit, a source of current for operating the means and the motors connected to the conductors and means for superimposing a plurality of currents of different but relatively fixed frequencies on said conductors to cause a selective operation of said switches to either of said positions.

3. A system of control comprising two conductors, a plurality of motors each separately and movably connected thereto, a switch movable with each motor for controlling the same, a source of current in fixed relation to said conductors, switch operating means for each switch, and means partly fixed in relation to said conductors and partly movable in relation thereto for superimposing currents of different characteristics from said first-mentioned current for selectively or simultaneously energizing said switch operating means.

4. A system of remote control comprising in combination, a plurality of electrically operable devices to be controlled, electrically operable selector means for each device including a switch having three positions, a source of current for operating said switches, each of said means including a relay for selectively connecting its

switch to a common circuit and sources of current for selectively actuating said relays independent of said switch operating current.

5. A system of remote control comprising in combination, a plurality of electrically operable devices to be controlled, a common circuit to which each device is connected, electrically operable selector means for each device including a switch having at least three positions, a source of current for operating said switches, each of said means including a selective relay for controlling the movement of each switch, and means for selectively impressing any one or more currents of different frequencies on said circuit for selectively controlling any one or more of said relays.

6. A system of control comprising two conductors, a motor connected thereto, a reversing switch, a plurality of switch operating means for each switch, means for selectively connecting said switch operating means to said conductors thereby operating the switch to a selected position to cause said motor to be operated in a desired manner, a source of current connected to said conductors for operating the motor and said switch operating means, and means for superimposing an additional current on said conductors to actuate said means for selectively connecting said switch operating means to thereby actuate said reversing switch without disconnecting the operating current from the conductors.

7. A system of control comprising a circuit, a motor connected thereto, a switch for said motor having at least three positions, switch operating means adapted to be connected to said circuit, means in parallel with said circuit for connecting said switch operating means to the circuit, and means for producing at least three currents of differing characteristics for energizing said connecting means, and means for selectively impressing any number of said currents on said circuit.

8. A switch device for remote control circuits comprising a plurality of coils having cooperative armatures, contact mechanism having an equal plurality of positions, means connecting said armature to said contact mechanism, a device in circuit with said contacts and a source of current and means independent of said current source for selectively energizing the coils in any desired sequence.

JOHN B. N. CARDOZA.
